TONGS FOR HANDLING GLASSWARE

Filed Sept. 15, 1937

UNITED STATES PATENT OFFICE

2,176,251

TONGS FOR HANDLING GLASSWARE

Frederick William Duhan, Baltimore, Md., assignor to Crown Cork & Seal Company, Inc., Baltimore, Md., a corporation of New York

Application September 15, 1937, Serial No. 164,048

15 Claims. (Cl. 294—90)

This invention relates to a new and improved construction of glassware handling tongs, adapted for use in mechanism for moving articles of glassware from one place to another. Although shown in the accompanying drawing as a part of a conventional forming machine take-out mechanism, the tongs of the invention are not limited to such use. On the contrary, they are readily adapted for use in performing other of glassware handling functions, such as transferring parisons to blow molds or grasping and supporting the ware in a lehr stacker, or the like.

It is an object of the invention to provide glassware handling tongs characterized by the absence of positive power means for closing the jaws. To this end, the jaws are closed, or moved to article engaging position merely by their own weight, or, in some cases, with the assistance of a like leaf spring.

20 A further object of the invention is to provide article engaging jaws which are maintained in their closed position by the weight of the supported article of glassware, and in which no positive power means are used to hold the jaws in engagement with the ware.

It is a further object of the invention to provide tongs which are readily adjustable for use with differently sized articles of glassware. To this end, the jaw members of the tongs are interchangeable with jaw members of other sizes, so that the contour of the article engaging surfaces may be changed to correspond to the shape of the ware. Moreover, the supports for the jaw members may be shifted toward and away from each other to vary the space between the supports, thereby to accommodate the differently sized jaws and to vary the space between the article engaging surfaces of the jaws to accommodate differently sized articles.

40 In the accompanying drawing, a preferred embodiment of the invention is shown, but it must be understood that the drawings and the following description are illustrative only, since many changes from the embodiment disclosed will readily occur to one skilled in the art.

In the drawing:

Figure 1 is a front elevational view, partly in section, of the tongs of the present invention.

Figure 2 is a horizontal section taken on the line 2—2 of Figure 1.

Figure 3 is an end elevation of the device of Figure 1.

Figure 4 is a diagrammatic view of the tongs of the present invention associated with a known type of take-out device, showing the manner in

which the tongs cooperate with the other mechanisms.

In the past, it has been the standard practice in the art to use glassware engaging tongs which are closed about the neck of the glassware by air 5 motors, cams, links and levers, heavy springs, or the like. Since considerable force is used to close the jaws, the slightly plastic ware which they engage is often damaged, if the jaws do not grasp the ware accurately, or if the jaws get out of adjustment or if the size of the ware varies slightly. With such positively closed jaws, small depressions are often made adjacent the neck finish, 10 with the result that the ware is defective. In some cases, the jaws even squash the finish and 15 make the bottle necks oval in shape, because of the excessive pressure applied in closing.

Conventional glassware handling tongs usually comprise jaws pivoted from above, mounted to swing downwardly and inwardly about a common 20 pivotal axis to closed position. In accordance with the present invention, however, the jaws project inwardly from outwardly disposed spaced, horizontal pivoting axes. They swing under their own weight downwardly and inwardly about their 25 individual axes to closed position and drop down under the neck finish. They are held in closed position merely by their own weight and the weight of the glassware, assisted in some cases by a light leaf spring.

30 Referring to the accompanying drawing, a hanger 10 is mounted for lateral movement in a horizontal plane between a pick-up position A adjacent the forming machine or the like, and a discharge position B adjacent a conveyor C which 35 may lead to a lehr stacker or the like. The hanger 10, in addition to its lateral movement, is reciprocated vertically at the pick-up and discharge positions. A known mechanism for giving the hanger this movement is shown in Figure 4, and 40 will be briefly described below.

The hanger 10 is provided at its lower end with a crosshead 11, which may be in the form of a flat plate, serving as a slide. The crosshead carries a pair of depending arms 12 and 12', slidably mounted thereon. A shaft 13 is journaled at 14 in a depending boss 15 secured to the lower surface of the crosshead 11. The shaft 13 is provided with oppositely disposed threads 16, 17 at its opposite ends. The arms 12 and 12' are bored 50 as at 18, 18' and the bores are provided with threads, complementary in pitch to the threads 16, 17. One end of the shaft 13 may be squared as at 19, to receive a key, wrench, or the like. Obviously, when the shaft is rotated in one direc- 55

tion or the other, the arms 12 and 12' will be caused to slide toward or away from each other along the crosshead 11.

Each arm terminates at its lower end in a cylindrical enlargement 20 which is bored at 21 to receive a pivot pin or bolt 22. Each bolt 22 serves to support a jaw member 23. The jaw member 23 is bifurcated at its rear end and is provided with spaced bosses 24, 25 through which the bolt 22 extends. A nut 26 may be used to hold the parts in assembled relation.

Each jaw member is provided with an integral, rearwardly and upwardly extending tail piece 27 which engages the arm 12 to limit the downward swinging movement of the jaw. The jaw proper comprises an inwardly projecting and upwardly inclined portion 28 and a horizontal portion 29 terminating at its inner end and a ware engaging edge 30. As shown in Figure 2, the edge of each jaw is formed on a concave line, to correspond with the contour of the ware to be grasped.

A light leaf spring 31 may be secured to each arm to engage the outer surface of the tail piece 27, to urge the jaws to closed position.

Each jaw member is provided with an outwardly projecting lug 32 or the like, which serves as an abutment means by which the jaw member may be raised upwardly from the lower, article engaging position to the upper, release position. As shown in the drawing, the lug 32 is in the form of an outwardly projecting pin, but any equivalent construction may be substituted. The lugs 32 are adapted to cooperate with stationary abutment means 33 disposed adjacent the discharge position. When the hanger 10 and the tongs supported thereby descend at the discharge position, the downward movement of the abutments 32 is arrested, with the results that the jaws swing upwardly relative to the remainder of the tong structure. As a consequence, the ware is released and drops down onto the take-out conveyor C.

In Figure 4, the tongs of the present invention are shown in association with a known type of take-out. The hanger 10 is carried by a vertically movable piston 35, reciprocably mounted in a cylinder 36, supported for horizontal sliding movement on ways 37. The cylinder 36, or its supporting structure is adapted to be reciprocated horizontally on the ways 37 by means of a piston rod 38 connected to piston 39 disposed within a horizontal cylinder 40. The cylinder 40 is supported from any appropriate standard 41 and the entire assembly may be braced by a guy rod 42 or the like. Air under pressure is adapted to be delivered from a conventional timer, in a predetermined cycle to the opposite ends of the cylinders 36 and 40 in such a manner that the hanger 10 and the tongs supported thereby move horizontally toward the pick-up position A, whereupon the piston 35 is depressed to permit the tongs to engage the article to be picked up. The piston 35 then ascends lifting the ware with it. The piston 39 then moves toward the left and the ware is moved to a position over the take-out conveyor C. The piston 35 again descends, and the lugs 32 associated with the jaws come in contact with the stationary abutments 33, to open the jaws and permit the ware to drop down on the conveyor.

Since it will be readily apparent to one skilled in the art how the air lines should be arranged and timed to effect the desired cycle of operations of the cylinders, the lines and the timer

are not disclosed herein. Moreover, any other means may be employed for imparting the desired movement to the hanger 10. For instance, the hanger may be supported by a laterally movable horizontally swinging arm which, at predetermined points in its lateral movement is given the desired vertical movements. Thus, the invention is not limited to use with an air operated take-out, but may be employed in a mechanically operated apparatus of any type.

The pick-up and discharge operations will now be described. Referring to Figure 1, when the assembly shown therein is moved downwardly over an article to be grasped, the under surfaces of the jaws 23 will engage the top of the article. As the downward movement continues, the jaws will be swung about the axes of the bolts 22 in an upward and outward direction until the ware engaging edges 30 of the jaws pass the neck finish on the article. Thereupon, the jaws will swing inwardly and downwardly to a position under the finish. This action will be accomplished by the weight of the jaws and will be assisted by the light springs 31. When the tongs are raised, the edges 30 will engage under the finish and the article will be raised with the tongs. The tongs are maintained closed by the weight of the bottle and no positive force is used. If a somewhat over-sized article is engaged by the tongs, therefore, the force tending to close the jaws will be relatively slight, and the article will not be damaged, but it will be impossible for the jaws to lose their grip on the article.

When the tongs and the article supported thereby have been conveyed to the discharge position, the tongs will descend and the lugs or abutments 32 associated with the jaws will come in contact with the stationary abutment 33 whereby the continued downward movement of the jaws is prevented. As a result, they will be swung relatively upwardly until the edges 30 move outwardly from the neck finish, whereupon the ware will be released and permitted to drop down onto the take-out conveyor.

I claim:

1. A tong assembly for use in a glassware take-out apparatus of the type including a laterally movable and vertically reciprocable hanger, and a crosshead secured thereto, said tong assembly being adapted to be carried by the crosshead and comprising a pair of jaws pivoted about spaced parallel axes for swinging movement between a lower, ware engaging position and an upper, release position, means for limiting the downward movement of the jaws at said lower position, and abutment means associated with said jaws adapted to engage stationary abutment means adjacent the ware discharging position upon the downward movement of vertical reciprocation of the hanger to effect a relative upward swinging movement of the jaws from the ware engaging position to the release position, thereby to discharge the ware held by said jaws.

2. A tong assembly for use in a take-out apparatus of the class including a laterally and vertically movable member, said assembly comprising a pair of spaced, parallel arms adapted to be mounted on said member and to project therefrom, a pair of jaws, one pivoted to each of said arms and having their ware engaging surfaces projecting towards each other, said jaws being mounted for upward and outward swinging movement between a lower, ware engaging position and an upper, release position, and means for moving said jaws upwardly upon downward

movement of said member at the discharge position to release the ware supported thereby.

3. For use in a take-out device for glassware forming machines and the like of the type wherein a ware handling unit is moved laterally from the forming machine to a discharge position spaced therefrom, a tong structure comprising a vertically movable crosshead, a pair of spaced, parallel arms depending therefrom, jaws pivoted to the arms for upward and outward swinging movement from a lower ware engaging position to an upper discharge position and means associated with said jaws for engaging a stationary abutment adjacent the discharge position upon descent of said crosshead to swing the jaws upwardly to said release position to release the ware carried thereby.

4. In a take-out mechanism of the type wherein in a member is adapted to be moved along a substantially horizontal path from a take-out position adjacent a forming machine to a discharge position over a conveyor and to be reciprocated vertically at said positions, a tong assembly adapted to be opened and closed at the discharge position, said tong assembly comprising a pair of inwardly projecting, upwardly and outwardly swinging jaws pivoted on outwardly disposed spaced parallel horizontal axes and having ware engaging surfaces facing each other, said jaws having abutment surfaces adapted to engage stationary abutment means upon downward reciprocating movement of said jaws adjacent the discharge position, to swing said jaws relatively upwardly and outwardly to release the ware held thereby.

5. Glassware handling tongs and means for opening the same comprising a laterally projecting crosshead and a carrier therefore, a pair of spaced slidably mounted arms projecting from the crosshead, means for positioning the arms at different points along the crosshead to vary the space therebetween, a pair of jaws projecting inwardly toward each other from outwardly disposed pivotal connections on said arms and mounted for swinging movement upwardly and outwardly from a ware grasping position to a release position, abutment surfaces on the jaws and means adjacent the ware discharge position adapted to be engaged by said abutment surfaces to swing the jaws upwardly and outwardly to release the ware.

6. Glassware handling tongs comprising a laterally projecting crosshead and a carrier therefore, a pair of spaced slidably mounted arms projecting from the crosshead, means for positioning the arms at different points along the crosshead to vary the space therebetween, a pair of jaws projecting inwardly from outwardly disposed pivotal connections on said arms, and mounted for swinging movement upwardly and outwardly from a ware gripping position to a release position, and abutment surfaces on the jaws adapted to cooperate with abutments adjacent the ware discharge position to swing the jaws upwardly and outwardly to release the ware.

7. Glassware handling tongs adapted to be associated with a movable member of a take-out device or the like which includes means for moving the member laterally from a pick-up position to a discharge position, said tongs comprising a crosshead supported thereon, a pair of slidably mounted arms projecting from said crosshead, means for shifting the arms toward and from each other along the crosshead to vary the space therebetween, pivotally mounted jaws on the

arms projecting towards each other to engage and support an article of glassware therebetween, said jaws being mounted for swinging movement upwardly from a ware gripping position to a ware release position, each of said jaws having a laterally projecting lug associated therewith adapted to cooperate with abutment means positioned adjacent the discharge position to effect a relative upward swinging movement of the jaws to ware release position.

8. Glassware handling means comprising a substantially horizontal crosshead, a pair of arms having portions slidably engaging the crosshead, a shaft extending through the arms and having oppositely disposed screw threads engaging complementary threads associated with the respective arms, and a pair of inwardly projecting jaws pivotally mounted on said arms and mounted for upward and outward swinging movement from a ware supporting position to a release position, rotation of the shaft serving to shift the arms and jaws toward and from each other to vary the space between the jaws to accommodate articles of glassware of different diameters.

9. Glassware handling means comprising a substantially horizontal crosshead, a pair of arms slidably mounted on the crosshead, and a shaft rotatably connected to the crosshead and extending through the arms and having oppositely disposed screw threads engaging complementary threads associated with the respective arms, and a pair of inwardly projecting jaws pivoted on said arms and adapted to grasp articles of glassware therebetween, said jaws being removably mounted on the arms to facilitate substitution of differently sized jaws for differently sized articles, rotation of said shaft serving to shift the arms toward and from each other to vary the space therebetween in accordance with jaws to be used and the articles of glassware to be handled.

10. Glassware handling means comprising a substantially horizontal crosshead, a pair of arms slidably mounted on the crosshead, a shaft rotatably connected to the crosshead and extending through the arms and having oppositely disposed screw threads engaging complementary threads associated with the respective arms, said arms each having at its outer end a pivot pin removably secured thereto, and a pair of inwardly projecting jaws pivoted on said pins and adapted to grasp articles of glassware therebetween, said jaws being removable upon removal of said pins to facilitate substitution of differently sized jaws for differently sized articles, rotation of said shaft serving to shift the arms toward and from each other to vary the space therebetween in accordance with the jaws to be used and the articles of glassware to be handled.

11. A tong structure for handling glassware comprising spaced downwardly projecting arms and jaw members pivoted on the lower ends of the arms for upward and outward swinging movement from a lower ware supporting position to an upper release position, each of said members comprising an inwardly projecting article engaging portion and a tail piece adapted to engage the associated arm to limit the downward swinging movement of the jaw and to hold the same in article supporting position.

12. A tong structure for handling glassware comprising spaced downwardly projecting arms and jaw members pivoted on the lower ends of the arms for upward and outward swinging movement from a lower ware supporting posi-

- tion to an upper release position, each of said members comprising an inwardly projecting and upwardly inclined portion terminating at its inner end in a concave, article engaging edge normally disposed on a plane above the pivotal connection of the member with the arm, whereby, upon swinging movement of the members from the article supporting position, said edges move outwardly away from the supported ware.
- 10 13. In a take-out apparatus for handling glassware of the class wherein a tong carrier is mounted for movement laterally between a pick-up position and a discharge position, and for movement vertically at each of said positions, the combination with said carrier of tongs comprising jaws projecting inwardly from outwardly disposed spaced pivoting axes and having their ware engaging surfaces disposed at least as high as said axes, said jaws being mounted to swing relatively upwardly and outwardly upon contact with the upper end of an article of glassware upon descent of the tongs at the pick-up position and then to swing relatively downwardly and inwardly under the neck finish of the article to grasp and support the ware upon ascent of the tongs.
- 15 14. In a take-out apparatus for handling glassware of the class wherein a tong carrier is mounted for movement laterally between a pick-up position and a discharge position, and for movement vertically at each of said positions, the combination with said carrier of tongs comprising jaws projecting inwardly from outwardly disposed pivoting axes and having their ware engaging surfaces disposed at least as high as said axes, said jaws being mounted to swing relatively upwardly and outwardly upon contact with the upper end of an article of glassware upon descent of the tongs at the pick-up position and then to swing relatively downwardly and inwardly under the neck finish of the article to grasp and support the ware upon ascent of the tongs.
- 20 15. In a take-out apparatus of the class wherein an article engaging tong structure is mounted for movement laterally between a pick-up point and a discharge point and for raising and lowering movement at each of said points, a tong assembly comprising jaws projecting inwardly from outwardly disposed, spaced pivots, the jaws being mounted to swing upwardly and outwardly from an article engaging position to a release position, and stationary abutment means adjacent the discharge point positioned to engage the jaws upon descent of the tong assembly to swing the jaws upwardly and outwardly to release the ware.
- 25 16. In a take-out apparatus of the class wherein an article engaging tong structure is mounted for movement laterally between a pick-up point and a discharge point and for raising and lowering movement at each of said points, a tong assembly comprising jaws projecting inwardly from outwardly disposed, spaced pivots, the jaws being mounted to swing upwardly and outwardly from an article engaging position to a release position, and stationary abutment means adjacent the discharge point positioned to engage the jaws upon descent of the tong assembly to swing the jaws upwardly and outwardly to release the ware.
